UNITED STATES PATENT OFFICE.

THOMAS J. MURPHY, OF ASTORIA, NEW YORK, ASSIGNOR OF ONE-HALF TO JAMES P. B. DUFFY, OF ROCHESTER, NEW YORK.

PHONOGRAPH STOP.

Application filed April 3, 1924. Serial No. 704,008.

To all whom it may concern:

Be it known that I, THOMAS J. MURPHY, a subject of the King of Great Britain, and a resident of Astoria, in the county of 5 Queens and State of New York, have made an Invention Appertaining to a Phonograph Stop, which invention is fully set forth in the following specification.

My invention has for its object to provide 10 an efficient automatic means for stopping the operation of a phonograph. It may be used for stopping the operation of any motor that actuates the record table of a phonograph.

15 The invention may be contained in structures which in their details may be modified. To illustrate a practical application of my invention I have selected a phonograph stop mechanism for opening the circuit of an 20 electric motor that actuates the record table, as an example of structures containing my invention and shall describe it hereinafter. The structure selected for the purpose of an example is shown in the accompanying 25 drawing.

Fig. 1 is a sectional view of the stop mechanism. Fig. 2 illustrates the stop mechanism with parts thereof shown in one position. Fig. 3 illustrates the stop mechanism 30 having its parts shown in another position. Fig. 4 is a sectional view taken on the line 4-4 indicated in Fig. 2. Fig. 5 is a sectional view similar to that shown in Fig. 4 when the motor circuit has been opened. Fig. 6 is a sectional view taken on the line 35 6-6 indicated in Fig. 3. Fig. 7 is a view of a lever actuating part.

The automatic stop mechanism is contained within the sheet metal case 1 having 40 a cover 2, whereby the major part of the mechanism is completely enclosed. The case is located on the top of the cabinet and beneath the record table 3 and in proximity to the supporting base 4 of the tone arm 5.

45 An insulating block 7 having sockets 8 and 9, for the reception of conductors 10 and 11 of one side of the motor circuit, is located in an opening formed in one side of the case 1. A spring contact 12 is connected to the socket 8 and to the block 7 by means of the screw 13. A rigid arm 14 forms a limit stop to the flexible contact 12. The arm 14 is formed of a rigid piece of metal that is secured in position by means

55 of the screw 13. A flexible strip, forming the contact 15, is also connected to the block 7 and to the socket 9 by means of the screw 16. The elasticity of the contact strip 15 tends, normally, to maintain the contacts 12, 15 open and thus maintain the circuit 60 of the conductors 10 and 11 open.

The contact strip 15 is provided with flanged portions 17 that increase the rigidity of the outer end portion of the strip 15 leaving a flexible portion between the outer 65 end and the part that is secured to the block 7. A link 18 of insulating material is pivotally connected between the flanged portions 17. The other end of the link 18 is connected to a link 19 that is pivotally supported on the bottom of the case 1 by the pin 20. The links 18 and 19 form a toggle joint as between the pivot pin 20 and the contacting strip 15. A pair of stops 21 and 22 are struck up from the bottom of the case 70 for limiting the movements of the toggle joint whereby the contact 15 will be held closed when the pivot of the joint is located on one side of the center line of the toggle and the joint is against the stop 21, and the 75 contacts 12 and 15 will be opened when the joint is on the other side of the center line and against the stop 22. The joint will remain in either one of these positions by reason of the spring action of the contact 15 80 when it is placed against one or the other of the stops 21 and 22.

85 Means is provided for breaking the toggle joint so as to open the contacts 12 and 15 and thus break the circuit through the conductors 10 and 11 and consequently break the circuit through the motor of the phonograph. The said means may be manually operated or it may be automatically operated 90 at a predetermined time in the operation of the phonograph. The means operates upon one of the links of the toggle to throw the joint between the links to one position or the other, that is, against one or the other of the stops 21 and 22. This is accomplished by a bell crank lever 23 that is pivotally supported on the pin 20. It has an arm 24 that is connected to the link 19. The connection is made by a finger 25 located at the end of the arm 24 that extends into an opening 26 formed in the link 19. There is sufficient play between the edge of the opening 26 and the finger 25 to produce a 100 105

free snap movement of the toggle, due to the elasticity of the strip 15, when the toggle is shifted by the operation of the lever 23 from one side of the center line to the opposite side. Thus the contacts 12 and 15 may be opened by movement of the lever 23. The lever 23 extends outside of the record table so that it can be manually operated. The contacts are also automatically opened by means of the bell crank lever 27 which is pivotally supported within the case 1. It has an arm 28 in position to operate upon the toggle 19 to open the contacts 12 and 15. The arm has a finger 29 in position to force the arm 19 away from the stop 21.

The bell crank lever 27 also has an arm 29 that protrudes from the case 1 and towards the base 4 of the tone arm. A split collar 30 is secured to the tone arm 5 and consequently is carried thereby. A forked member 31 is pivotally and frictionally connected and secured to the collar 30. Suitable frictional washers 32 may be located on opposite sides of the forked members 31 and the parts may be secured together by suitable rivet or screw 33. The fingers 34 and 35 are bent downward so as to be located on opposite sides of the arm 29 of the bell crank lever 27 and so as to be engaged thereby, in so far as movement of the forked member 31 relative to the tone arm 5 is frictionally resisted. Thus the tone arm may be swung to a position that the re-producing needle will be located outside or beyond the edge of the record table and, in so doing, the finger 34 will engage the arm 29 so as to swing the member 31 on its pivot to a position beyond the second tripping position of the arm. The lever 29 being limited in its movement by the stop 36 which extends upward from the bottom of the case 1 into an opening 37 formed in the bell crank lever 27. The opening of the bell crank lever 27, sufficient to throw the toggle and permit the contacts 12 and 15 to open. When a record is about to be played the arm is swung inward until the needle is brought to a position on or above the plate at which point it is desired to have the machine stop in its operation. This inward movement brings the finger 35 into engagement with the arm 29 of the bell crank lever 27 and the forked member 31 is adjusted automatically to its tripping position. The tone arm 5 is then placed at the edge of the plate and in position to start the reproduction of the recorded sound of the record plate and the machine is started by the operation of the bell crank lever 23 which is moved so as to close the contacts 12 and 15. When the reproducing needle reaches the end of the record, the finger 35 engages the bell crank lever 27 and causes the switch that is thus formed to be tripped and break the

circuit of the motor, the switch opening with a snap action.

I claim:

1. In a stop mechanism for sound reproducing machines, the combination with a record support, driving means for the latter and a tone arm movable back and forth across a record on said support, of controlling means for said driving means comprising an actuating part located adjacent the tone arm and a device yieldably carried by the latter having spaced abutments for successive setting engagement with opposite sides of said actuating part during a back and forth movement of the tone arm to position said device for moving said part when the tone arm reaches the end of a record. 70

2. In a stop mechanism for sound reproducing machines, the combination with a record support, driving means for the latter and a tone arm movable back and forth across a record on said support, of controlling means for said driving means comprising a trip device having a tripping part, and a yoke yieldably carried by the tone arm having spaced abutments for successive setting engagement with opposite sides of said tripping part during a back and forth movement of the tone arm to position said yoke for moving said part when the tone arm reaches the end of a record. 85

3. In a stop mechanism for sound reproducing machines, the combination with a record support, driving means for the latter and a tone arm movable back and forth across a record on said support, of controlling means for said driving means comprising an actuating arm located adjacent the tone arm and a yoke pivotally supported on the tone arm by yieldable frictional means 100 for successive setting engagement with opposite sides of said tripping part during a back and forth movement of the tone arm to position said yoke for moving said arm when the tone arm reaches the end of a record. 105

4. In a stop mechanism for sound reproducing machines, the combination with a record support, driving means for the latter and a tone arm movable back and forth across a record on said support, of controlling means for said driving means comprising a pair of electric contacts, spring means for moving one of said contacts to separate the same, a toggle joint for resisting movement of said movable contact, a lever for breaking said toggle joint, and a device yieldably carried by the tone arm having spaced abutments for successive setting engagement with opposite sides of said lever during a back and forth movement of the tone arm to position said device for moving said lever when the tone arm reaches the end of a record. 115

5. In a stop mechanism for sound repro-

120

- ducing machines, the combination with a record support, driving means for the latter and a tone arm movable back and forth across a record on said support, of controlling means for said driving means comprising a pair of electric contacts, spring means for moving one of said contacts to separate the same, toggle arms connected with said movable contact, a stop for holding said 5 arms in alignment with said contacts engaged, a lever provided with stop means and having a limited movement for engaging and moving said arms out of alignment to release said movable contact, and a yoke 10 yieldably carried by the tone arm having spaced abutments for successive setting engagement with opposite sides of said lever during a back and forth movement of the tone arm to position said yoke for moving 15 said lever when the tone arm reaches the end of a record. 20
6. A stop mechanism for sound reproducing machines, comprising an electric switch, spring means tending to open the same, trip means for holding said switch closed, including an arm having a limited movement for actuating said trip means to release the switch, and a device adapted for yieldable actuation by the tone arm of the machine and provided with spaced abutments for successive setting engagement with opposite sides of said trip arm during a back and forth movement of the tone arm to position said device for moving said trip arm when the tone arm reaches the end of a record. 25
